(57) **CLAIM**

The ornamental design for a shed fence, as shown and described.

DESCRIPTION

FIG. 1 is a front, top and right side perspective view of a shed fence, showing my new design;

FIG. 2 is a rear, bottom and left side perspective view thereof;

FIG. 3 is a detached state perspective view of the shed fence;
FIG. 4 is a perspective view with the door opened of the shed fence;

FIG. 5 is a detached state perspective view with the door opened of the shed fence;

FIG. 6 is a front view thereof;

FIG. 7 is a rear view thereof;

FIG. 8 is a left side view thereof;

FIG. 9 is a right side view thereof;

FIG. 10 is a top plan view thereof; and

FIG. 11 is a bottom plan view thereof.

FIG. 12 is an enlarged view of portion 12 shown in FIG. 1.

FIG. 13 is an enlarged view of portion 13 shown in FIG. 2.

FIG. 14 is an enlarged view of portion 14 shown in FIG. 3.

FIG. 15 is an enlarged view of portion 15 shown in FIG. 4.

FIG. 16 is an enlarged view of portion 16 shown in FIG. 1.

FIG. 17 is an enlarged view of portion 17 shown in FIG. 2; and,

FIG. 18 is an enlarged view of portion 18 shown in FIG. 4.

The dash dot dash broken lines encircling subject matter depict boundaries of the enlarged view and form no part of the claim.

1 Claim, 18 Drawing Sheets
